ABRADANT AND HOLDER THEREFOR

John W. Gottschalk and Sylvester W. Grater,
Philadelphia, Pa.; said Grater assignor to said
Gottschalk, Annie Gottschalk executrix of
said John W. Gottschalk, deceased

Application October 7, 1932, Serial No. 636,679

1 Claim. (Cl. 15—209)

The object of our present invention is to devise a novel construction and arrangement of an abradant which can be attached to a handle so that instead of the user grasping the metallic bunch of abradant, a grasping handle is provided.

A further object of the invention is to devise a novel abradant wherein a metallic strand is used which may or may not be flattened or deformed in cross section and which has been formed into a helical coil. This is preferably accomplished by passing the abradant over a curling edge while under tension so that one surface of the abradant is stretched longitudinally of the strand thereby imparting to the strand, when released from tension, an inherent tendency to curl, or, in other words, to form a helical coil which is preferably continuous. The strand is then wound into an elongated tubular member and during the winding the tension is preferably such that juxtaposed coils of the strand interlock with each other throughout the mass of such member so that after the member is stretched it will, when released, return substantially to its normal formation. A fastening member, such as, for example, bent wire, has one end member inserted through the tubular member and the ends of such fastening member are then brought into proximity to each other thus providing two members which can be inserted in an aperture in a handle in which they are retained by any suitable fastening means. When this tubular cylinder of abradant is brought together in this manner the abradant is somewhat compressed and as the loops in proximity to the handle on opposite sides of such handle extend downwardly towards the free end of the handle, they are preferably turned over the prongs of the fastening device thus placing a tension on the bunch of abradant so that a flexible and resilient bunch is provided at the forward end of the handle, the juxtaposed strands of the bunch interlocking throughout the mass of abradant so that the bunch retains its bunch formation during the life of the bunch.

With the above and other objects in view, as will hereinafter more clearly appear, our invention comprehends a novel abradant, a novel method of making it, and novel means for securing it in bunch formation to a handle.

Other novel features of construction and advantage will hereinafter more clearly appear in the detailed description and the appended claim.

For the purpose of illustrating the invention, we have shown in the accompanying drawing 55 typical embodiments of it, which, in practice,

will give satisfactory and reliable results. It is, however, to be understood that the various instrumentalities of which our invention consists can be variously arranged and organized, and our invention is not limited to the exact arrangement and organization of these instrumentalities, as herein set forth.

Figure 1 is a diagrammatic view showing one step of the operation where the strand is being wound upon a mandrel.

Figure 2 is a side elevation of the interlocked strands after their removal from the mandrel.

Figure 3 is a front elevation of a fastening device.

Figure 4 shows another step of the operation where one prong of the fastening device has been inserted in the tubular member of the abradant.

Figure 5 shows the next step of the operation, showing in side elevation the abradant as it appears after the fastening device has been passed therethrough and the prongs bent into proximity to each other.

Figure 6 shows the next step of the operation, showing in side elevation the abradant and the fastening device after the end loop portions of the abradant have been passed over the prongs of the fastening device.

Figure 7 is a side elevation, partly in section, of the handle.

Figure 8 is a side elevation of the abradant and its handle in its assembled condition ready for use.

Figure 9 is a plan view of another embodiment of our invention.

Similar numerals of reference indicate corresponding parts.

Referring to the drawing:

1 designates a metallic strand which is in the form of a helical coil having an inherent tendency to curl and preferably formed by coiling it under tension. If desired, the strand may be passed over a curling edge under tension so that one surface of the strand is stretched and when the tension is released the strand forms a helical coil. We have deemed it unnecessary to illustrate the formation of the helical coil.

The strand passes through a reciprocatory carrier 2 and is wound around a revolving mandrel 3. This action of winding a coiled strand of this character around a mandrel where the wind changes its direction at each end of the stroke causes an intimate interlocking of the coils of juxtaposed strands so that a flexible and resilient cylindrical mass of abradant 4 is formed. In order to secure the abradant in bunch formation

we employ a fastening device 5, such as, for example, a wire or band which has been bent upon itself to form the prongs 6. One of the prongs 6 is passed through the tubular mass of abradant as shown in Figure 4, and it will be noted that it is necessary to longitudinally compress the abradant to have such prong pass through it. In other words, the tubular mass of abradant is preferably longer than the prong. The prongs 10 are then brought together as shown in Figure 5 and the two prongs are bent towards each other. This draws closely together the inner portions of the tubular mass of abradant while the outer portions deflect outwardly, but, of course, 15 they are all intimately interlocked as shown in Figure 5. It will be seen from this Figure 5 that the end portions are looser and less compact than the other portions of the bunch and the end portion at each side is stretched towards the 20 other side and looped over the prongs 6 so that the bunch of abradant and its fastening device now appear as shown in Figure 6 with the prongs 6 in close proximity to each other.

A simple and economical construction of 25 handle which can be employed consists of a piece of material 7, such as, for example, wood, bakelite, or any other desired material, having an aperture 8 opening through one end adapted to receive the prongs 6.

30 In Figure 8 we have shown the abradant and its fastening device as shown in Figure 6 inserted into the handle 7 thus showing the abradant and its handle in its completed condition.

Due to the characteristics of the coiled strand 35 and the manner in which juxtaposed strands interlock throughout the mass of the abradant, the device is especially adapted for use in place of the ordinary dish cloth as it does not scratch.

Our present invention, although especially 40 adapted for cleaning dishes and kitchen utensils, can be advantageously employed in cleaning and polishing any desired material.

In Figure 9 we have shown another embodiment of our invention in which the tubular member has a fastening device, such as, for example, a wire 9 which is passed through it and twisted, or otherwise fastened, and the free ends are inserted into the flexible and resilient metallic bunch thus formed by bending the free ends upon 50 themselves and deflecting them around the annu-

lar portion of such securing member. This embodiment, can, of course, be secured to a handle if desired or it can be used as a flexible and resilient metallic bunch adapted to be grasped by the hand of the user.

It will be noticed that in this form of our invention the coils of juxtaposed helical strand portions are interlocked so that the bunch can be stretched and scrubbed with soap and water or other cleansing material, and when released it will return to substantially its normal position.

10 In this form of our invention the helical strand portions are, in general, radially disposed although some of the strand portions extend in different directions especially after the flexible and resilient metallic bunch has been worked together by subjecting it to pressure either mechanically or by the hands of the operator.

15 It will now be apparent that we have devised a new and useful abradant and holder therefor which embodies the features of advantage enumerated as desirable in the statement of the invention and the above description, and while we have, in the present instance, shown and described preferred embodiments thereof which will give in practice satisfactory and reliable results, it is to be understood that these embodiments are susceptible of modification in various particulars without departing from the spirit or scope of the invention as claimed or sacrificing any of its advantages.

20 Having thus described our invention what we claim as new and desire to secure by Letters Patent, is:—

25 A flexible and resilient metallic bunch and holder therefor comprising an open ended tubular bunch of a coreless helical metallic strand with juxtaposed coils interlocked, and the holder comprising a straight stiff strand bent upon itself to form a loop and prongs, with the prongs passing 40 through the bunch and with the loop at the center of the bunch, and having the prongs extending beyond the bunch and compressing the portion of the bunch between them from the center towards its outer periphery with the loose 45 strands of the tubular bunch at one side of a prong passed over the other prong and interlocked with the juxtaposed coils of the bunch.

JOHN W. GOTTSCHALK.
